UNITED STATES PATENT OFFICE.

GUSTAV PIELSTICK, OF AUGSBURG, GERMANY, ASSIGNOR TO THE FIRM: MASCHINEN-FABRIK AUGSBURG-NUERNEBERG, AKTIENGESELLSCHAFT, OF AUGSBURG, GERMANY, A CORPORATION OF GERMANY.

COMPRESSED-AIR STARTING DEVICE FOR INTERNAL-COMBUSTION ENGINES.

Application filed March 10, 1923. Serial No. 624,218.

To all whom it may concern:

Be it known that I, GUSTAV PIELSTICK, a citizen of the German Republic, and a resident of 7 Stadtbachstrasse, Augsburg, Bavaria, Germany, have invented certain new and useful Improvements in Compressed-Air Starting Devices for Internal-Combustion Engines, of which the following is a specification.

10 This invention relates to a compressed air starting device for internal combustion engines, and its main object is the provision of improved air controlled means to facilitate the actuation of the starting valve during the starting period.

With this object in view, the invention involves the provision of a lever for actuating the starting valve which is continuously rocked by a cam and cam lever. The actuating lever engages the stem of the starting valve, but under ordinary conditions the connection between the actuating lever and the stem of the valve is such that the rocking movement of the lever does not affect the position of the valve. Air control means, however, are provided for establishing a different operative connection between the actuating lever and the valve, so that when these means are effective the rocking movement of the actuating lever produced by the cam lever causes the valve to open and close in correspondence with the movement of the cam lever. When the engine is running on fuel these air control means are restored to their original positions so that the valve-actuating lever may again rock without actuating the air valve.

Further objects and advantages of the invention will be apparent from the following description of the appended drawing, in which

Fig. 1 is a vertical section, with parts shown in elevation, of the new starting device,

45 Fig. 1^a is a cross section through the valve spindle on the line A—B of Fig. 1,

Fig. 2 shows a slightly modified form of the valve operating rocking lever,

50 Fig. 3 is a view similar to Fig. 1, showing the relative position of the different parts of the mechanism during the starting operation.

Referring first to Fig. 1: α denotes the cylinder head of an internal combustion en-

gine having its starting valve b arranged 55 in the usual manner. Said valve is provided with a relief portion c and is normally held closed by the action of a compression spring d . That part of the valve spindle which projects above the cylinder head is 60 provided with two superposed slots e and f , through which the two levers g and h pass; the former being the valve operating rocking lever pivoted at i to the cam lever k . This cam lever is in the shape of a two-armed lever and is controlled by a roller l and cam m . The auxiliary lever h is fulcrumed to a lug n of the cam lever and, with one of its ends, is connected to lever g by means of a link o so that a closed link drive 65 is formed in this way consisting of the four members n, g, o, h . The uppermost portion of the valve spindle is made to form a cylinder p within which a piston q is arranged to slide loosely and to rest upon lever h . 70 The valve spindle is provided with a passage r , which has its entrance opening opposite the compressed air conduit s and which terminates into the cylinder p above piston q .

75 The new starting device operates as follows: Under normal working conditions the various parts of the device are at rest and in the position shown in Fig. 1. Valve b is held closed by its spring d and there is no compressed air in the cylinder to act on the piston which, therefore, only rests with its own weight upon lever h . It will be seen that in this position of the parts, lever g is able to follow the movement of the cam lever by rocking on its support in the slot e of the valve spindle, without thereby actuating the valve, as the actuating gear g, h is able to yield by simply displacing the piston q .

90 When now the engine is started, the compressed air enters from s through the passage r into the cylinder p above piston q . The pressure of the air then forces the piston firmly against lever h , thus preventing it from swinging upwardly, and at the same time also preventing the free end of lever g from moving aside when being rocked. The pivot t now serves as a fulcrum on which lever g may rock under the 95 action of the cam lever k and thereby open the valve by pressing it downwardly against the resistance of its spring d . This action 100 105

is repeated at every rotation of the cam shaft as long as compressed air is admitted, i. e. until the engine begins to work on fuel.

Lever *h* is provided with a set screw *u* adapted to bear against the shorter arm of cam lever *k* and to thereby adjust roller *l* in relation to cam *m*. A spring *v* fastened to the lever *k* and acting on an extended arm of lever *h* serves to relieve the cam to 10 some extent during the normal work of the engine.

What I claim is:—

1. In a compressed air starting device for internal combustion engines the combination 15 with a starting valve, a cam and a cam lever, of a valve operating rocking lever pivoted to the cam lever and resting loosely upon a portion of the valve spindle, an auxiliary lever, means to connect both the latter levers

20 at their free ends, a cylinder on the valve spindle, a loosely mounted piston in said cylinder, passage ways for compressed air in the valve spindle terminating in the cylinder, said piston adapted to press said auxiliary lever against the valve spindle.

2. In a compressed air starting device for internal combustion engines, in combination with a starting valve, a cam and a cam lever, of a valve operating rocking lever pivoted to 25 the cam lever and passing loosely through a slot in the valve spindle, an auxiliary lever pivoted to a lug on the cam lever and passing through another slot in the valve spindle, a link to connect the free ends of both the latter levers, a cylinder on the valve spindle, a loosely slideable piston in said cylinder, an air passage in the valve spindle terminating in the cylinder at a point above the piston, and a spring to normally keep the valve 40 closed, said piston, when under pressure, adapted to press said auxiliary lever against the valve spindle.

3. In a compressed air starting device for 45 internal combustion engines, a valve operating closed link drive consisting of a cam lever, a loosely mounted rocking lever pivotally connected at one of its ends to the cam lever, an auxiliary lever also pivotally connected to the cam lever and disposed 50 approximately parallel to the said rocking lever, pneumatic means to block said auxiliary lever during the starting period of the engine, a link to connect the free ends of both the latter levers and to serve as a fulcrum for the rocking lever when the auxiliary lever is in its blocked position, and 55 means to rock said rocking lever on its link connection to depress the valve against the resistance of the valve spring.

4. In a compressed air starting device for 60 internal combustion engines, a valve operating closed link drive consisting of a cam lever, a loosely mounted rocking lever pivotally connected at one of its ends to the cam lever, an auxiliary lever also pivotally 65 connected to the cam lever, a cylinder carried by the valve spindle and in communication with the starting air conduit by means of a passage in the valve spindle, a piston mounted to loosely slide in the cylinder and 70 to block the auxiliary lever during the starting period of the engine, a link to connect the free ends of both the said levers, latter link normally permitting the rocking lever to move under the action of the cam lever, without actuating the valve and to serve as a fulcrum for the rocking lever when the auxiliary lever is in its blocked position, and 75 means to rock the rocking lever on said fulcrum in order to depress the valve.

5. In a compressed air starting device for 80 internal combustion engines, a valve operating closed link drive consisting of a cam lever, a loosely mounted rocking lever pivot- 85 ed at one of its ends to the cam lever, an auxiliary lever also pivotally connected to the cam lever, a set screw between the cam lever and the auxiliary lever to adjust the position of the cam roller, pneumatic means to block the auxiliary lever during the starting period of the engine, a link pivotally connecting the free ends of the said rocking and auxiliary levers and to serve as a fulcrum for the rocking lever when the auxiliary lever is in its blocked position. 90

6. In a compressed air starting device for 95 internal combustion engines, a valve operating closed link drive consisting of a cam lever, a loosely mounted rocking lever pivot- 100 ed at one of its ends to the cam lever, an auxiliary lever also pivotally connected to the cam lever, an extension to the auxiliary lever, a resilient connection between said extension and the cam lever, pneumatic means to block the auxiliary lever during the starting period of the engine, a link to connect the free ends of the said rocking and auxiliary levers and to serve as a fulcrum for the former when the latter is in its blocked position. 105

In testimony whereof I have hereunto set my hand, in the presence of two subscribing witnesses.

GUSTAV PIELSTICK.
